United States Patent Office.

HENRY C. GRIGGS, OF WATERBURY, CONNECTICUT, ASSIGNOR TO HOLMES, GRIGGS & SMITH, OF THE SAME PLACE.

Letters Patent No. 66,324, dated July 2, 1867.

IMPROVEMENT IN BUCKLES.

The Schedule referred to in these Letters Patent and making part of the same.

TO ALL WHOM IT MAY CONCERN:

Be it known that I, HENRY C. GRIGGS, of Waterbury, in the county of New Haven, and State of Connecticut, have invented a new Improvement in Buckles; and I do hereby declare the following, when taken in connection with the accompanying drawings, and the letters of reference marked thereon, to be a full, clear, and exact description of the same, and which said drawings constitute part of this specification, and represent, in—

Figure 1, a face or outside view of the buckle complete.

Figure 2, a face view of the plate or frame.

Figure 3, a face view of the tongue.

Figure 4, a transverse section of the plate.

Figure 5, a transverse section of the tongue.

Figure 6, a transverse view of the buckle complete; and in

Figures 7, 8, and 9, its operation.

This invention relates to an improvement in that class of buckles used in wearing apparel, and designed with more especial reference to hoop-skirt bands, and consists in the peculiar construction of the frame and tongue, whereby the loop formed upon the tongue drops through the plate, so that the tongue bears upon the upper surface of the plate; and the strain upon the loop of the tongue tends to bear the tongue more firmly upon the strap.

In order to the clear understanding of my invention, I will proceed to describe the same as illustrated in the accompanying drawings.

A is the frame, constructed from sheet metal or other suitable material, formed with a central slot, a, (see fig. 2,) and a loop, d and d', upon either side. B, the tongue formed from sheet metal, or other suitable material, and provided with shoulders, f, and a loop, C, the frame of the said loop corresponding to the length of the slot a in the plate, and so as to be set freely therethrough, as seen in fig. 6, and the shoulders f to rest upon the face of the plate A. The tongue B is curved, as seen in fig. 5, so that the bar h of the loop will drop below the plate, as seen in figs. 5 and 6, and so that the strap D may be securely fixed to the bar h, as seen in fig. 7, and when the strap is so attached the tongue cannot be removed from the frame, and yet the tongue may be freely turned up, as seen in fig. 8, or down, as in fig. 7. The strap D being attached as before described, the other end of the said strap (or another strap, as the case may be,) is inserted upward through the slot d, as seen in fig. 8, and over the tongue, may be passed through the slot d', which serves as a loop to hold the end of the strap. The slot d' is not essential. The strain upon the strap draws the tongue hard down upon the strap, as seen in fig. 9, and firmly binds and holds the strap in that position. To unloose the strap, simply draw back the end, as seen in fig. 8, and the tongue freely rises to permit the loosening of the strap.

By this construction the buckle may be formed entirely by machinery, and at but two or three operations; is but little thicker when complete than the metal itself from which the frame is formed, is extremely light, and neat and tasteful in its appearance. It will be observed that the tongue is not secured into the frame, except by the attachment of the strap to the loop of the tongue; yet, if deemed expedient, the tongue may be bent or curved, or by an additional operation after its insertion through the plate, to prevent such removal. This adds to the cost of manufacture, and is not essential to the trade or to the convenience of the user.

Having thus fully described my invention, what I claim as new and useful, and desire to secure by Letters Patent, is—

The herein-described buckle, consisting of the plate or frame A, and the looped tongue B, formed so as to be inserted through the plate, and to operate substantially in the manner herein set forth.

HENRY C. GRIGGS.
